DESIGN FOR A DRAFTSMAN'S INSTRUMENT RACK

Jacque Fresco, Los Angeles, Calif.

Application April 2, 1946, Serial No. 128,179

Term of patent 14 years

(Cl. D74—13)

To all whom it may concern:

Be it known that I, Jacque Fresco, a citizen of the United States, residing at Los Angeles, county of Los Angeles, and State of California, have invented a new, original, and ornamental Design for a Draftsman's Instrument Rack, of which the following is a specification, reference being had to the accompanying drawing, forming part thereof.

Fig. 1 is a three-quarter perspective view of the draftsman's instrument rack showing my new design.

Fig. 2 is an end view thereof.

I claim;

The ornamental design for a draftsman's instrument rack, substantially as shown.

JACQUE FRESCO.
